ATTORNEY

UNITED STATES PATENT OFFICE

GUSTAVE E. VILLARET, OF LEONIA, NEW JERSEY, ASSIGNOR TO MARKEL ELECTRIC PRODUCTS, INC., OF BUFFALO, NEW YORK, A CORPORATION OF NEW YORK

DESIGN FOR AN ELECTRIC-LIGHT BRACKET

Application filed November 5, 1929. Serial No. 33,341. Term of patent 3½ years.

To all whom it may concern:

Be it known that I, GUSTAVE E. VILLARET, a citizen of the United States, residing at Leonia, in the county of Bergen and State of New Jersey, have invented a new, original, and ornamental Design for an Electric-Light Bracket, of which the following is a specification, reference being had to the accompanying drawing, forming part thereof.

In said drawing:

Figure 1 is a front elevation of an electric light bracket embodying my new design.

Figure 2 is a side elevation of the same.

I claim:

The ornamental design for an electric light bracket, substantially as shown and described.

GUSTAVE E. VILLARET.
